UNITED STATES PATENT OFFICE

EDWARD J. BRANDT, OF WATERTOWN, WISCONSIN, ASSIGNOR TO BRANDT AUTOMATIC
CASHIER COMPANY, OF WATERTOWN, WISCONSIN

COIN DELIVERY MACHINE

Application filed December 10, 1928. Serial No. 325,063.

This invention relates to a coin delivery machine.

In coin delivery machines as heretofore constructed, it is the usual practice to provide a coin delivery tray having a plurality of coin channels, each coin channel carrying coins of a certain denomination. It is desirable, in these machines, under certain conditions to provide for the discharge of more than one coin of the same denomination. Heretofore, this has been accomplished either by providing a plurality of coin channels for coins of the same denomination, or by providing for the discharge of a plurality of coins from one channel. In either case, duplication of channels is required, which materially increases the bulk and mechanism of the machine.

This invention is designed to overcome the defects noted above, and objects of the invention are to provide a coin delivery machine which is so made that a coin tray provided with channels for coins of different denominations has one or more of these channels provided with means governing the number of coins ejected therefrom, such means normally permitting the ejection of a single coin, but under other conditions permitting the discharge of a plurality of coins of a predetermined number.

More specifically, objects of this invention are to provide a coin delivery machine in which key controlled mechanisms operate ejectors which are associated with the different coin channels, and to provide one coin channel with two ejectors located at different heights, and to equip such coin channel with a movable member normally allowing the discharge of a single coin, but when a certain one of the ejectors is operated, permitting the discharge of a predetermined number of coins.

A still further object of the invention resides in the provision of positive means associated with a coin channel to control the discharge of a varying number of coins therefrom.

With the above and other objects in view, which appear as the description proceeds, the invention resides in the novel construction,

combination and arrangement of parts substantially as hereinafter described and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

An embodiment of the invention is shown in the accompanying drawings in which:

Figure 1 is a sectional view through a coin discharge machine with the machine in normal position;

Figure 2 is a face view of the coin channels;

Figure 3 is a fragmentary, sectional view on the line 3-3 of Figure 2;

Figure 4 is a sectional view through the lower portion of one of the channels;

Figure 5 is a sectional view on the line 5-5 of Figure 1.

Figure 6 is a plan section taken on the lines 6-6 of Figures 2 and 4.

Referring to the drawings, it will be seen that the coin delivery machine is provided with a plurality of key operated mechanisms, each mechanism including a key lever 1, provided with a key 2 and pivotally mounted at a relatively elevated point upon the shaft or pivot pin 3. The key lever may take different forms, but in the form shown, it is provided with a downwardly projecting extension 4 which operates a selector 5. The selector is carried by a rocking member 6 and at its rear end actuates the lower end of the ejector lever 7. This ejector lever has its upper end held normally against a stop 8 by means of a spring 9. Each ejector lever is provided with an ejector 10, urged upwardly by means of the spring 11. These ejectors cooperate with a plurality of coin channels 12, and each coin channel is provided with partition plates 13 which terminate in inwardly directed lips 14. The lips 14 are spaced from the upper edge of the

80

90

95

100

base 15, as may be seen from Figure 2, and thus allow the discharge of a coin when the appropriate ejector is operated. The ejector, in each case, is carried within a notch formed in the base 15.

8 One or more of the channels is provided with a relatively large notch 16 which carries a pair of ejectors 10 and 17, the ejector 10 being shown in Figure 1.

10 It is to be noted from Figure 2 that the ejector 10 stands at a greater height than the ejector 17, so that the lower ejector will engage a single coin and the higher ejector will engage a plurality of coins. The coins 15 may be ejected, under normal conditions, only singly, due to the lips 14. One of the lips, however, is provided with a cut-away lower portion and is supplemented by a sliding lip 18 (see Figures 2 and 4). This sliding lip 18 is seated within a recess formed in the stationary lip 14 and in effect, normally forms a continuation of such stationary lip. It is urged downwardly to its lowest position, as shown in Figures 2 and 4, by means 20 of a spring 19 carried in any suitable manner, for instance, within a tubular member 20. This member 20 may be slotted to receive the movable lip 18, and may have a relatively wide slot cut at its upper edge to 25 receive the partition 13.

30 The slot 22 is formed in the lip 14, with its lower edge flush with the lower edge of the lip 18. However, it will be noted that the supporting surface of the base 15 is 35 spaced below the lower edges of the slot 22 and the lip 18, thus normally allowing a single coin to be ejected beneath the lip 18. However, a second coin is prevented from being ejected through the slot 22 by the lip 40 18 until the latter is raised upon actuation of the ejector lever 7. That portion of the partition 13 forming the lip 14 above the slot 22 is curved, as shown in Figure 3, while the portion below the slot engaging the base, extends straight outwardly. Thus, as 45 shown in Figure 6, although the lip 14 at the opposite side of the channel is not cut out, the second coin will be permitted to project through the exposed slot 22 and follow the 50 contour of the partition adjacent, which is concentric with the lip 14 at the opposite side of the channel, and which is not cut away, thus allowing the ejector to force the coin past the lip 14, as there is sufficient room 55 between this lip and the lip of the partition of the channel adjacent the finger 18. Obviously, when the gate 18 covers the slot 22, the same cooperates with the opposite lip 14 to retain the second coin.

60 As shown more clearly in Figures 3 and 4, the partition 13 is cut away, as indicated at 21, to provide room for the tubular member 20. The movable finger 18 is provided with a cut-away lower portion or face 22 (see 65 Figure 4), which is spaced the thickness of

one coin from the base, while the bottom of the movable member 18 normally rests upon the base, which is provided with a slot through which a finger 23, integral with the lip 18, slidably passes.

70 It is apparent from the description thus far given that when the lip 18 is in its normal or lowest position, that a single coin only may be discharged. When the lip is raised to its uppermost position and the ejector 10 operated, a predetermined number of coins are discharged, for example, two coins.

75 The means for elevating the movable lip 18 may take different forms. However, in the form illustrated in Figure 1, a plunger 24, suitably guided, contacts with the lower end of the tongue 23. The plunger 24 is elevated by means of a small flap 25 actuated by a cam 26, carried by a rock shaft 27, which is provided with a pin 28, connected by means of a spring 29, to a stationary portion of the machine, such spring returning the cam shaft to its initial position, as shown in Figure 1, after each operation of the shaft. This shaft is also provided with a pin 30 connected by means of a link 31 with the lever 7 of the higher ejector 10.

80 It is apparent, therefore, that when the lower ejector is operated, the machine functions in its normal manner, and allows the discharge of a single coin. When the appropriate key, however, is depressed, the ejector 10 is operated and engages two coins.

85 In addition to this, the rock shaft 27 has a 90 rocking motion imparted thereto by means of the link 31 and pin 30, and thus elevate the plunger 24. The plunger in turn lifts the movable lip 18 to its uppermost position and allows the two coins to pass from the 95 coin channel.

100 It is thus apparent that a novel form of coin delivery machine has been provided by this invention which does not necessitate a plurality of coin channels for coins of the same denomination, but which, instead, has 110 mechanism so constructed and associated with the coin channel that it ordinarily moves the restraining lip upwardly and discharges a plurality of coins.

105 Further, while it will be noted that the 115 machine is very easy to operate and is of simple construction, the same provides for a positive selective control of the number of coins to be discharged from one or more channels.

120 I claim:

125 In a coin delivery machine, a coin tray having a coin channel, said channel having a notched base two ejectors located within the notch of said base and positioned at different heights, levers associated with each ejector, key controlled mechanism for actuating said levers to selectively operate the same, a slide carried by said channel for positively controlling the discharge of coins therefrom, 130

means actuated by one of said ejectors for actuating said slide, said slide having a downwardly extending tongue, a rock shaft provided with a cam, mechanism operatively connecting said cam and said downwardly extending tongue, and means operatively connecting said rock shaft with the upper of said ejectors.

5 In testimony that I claim the foregoing I have hereunto set my hand at Watertown,
10 in the county of Jefferson and State of Wisconsin.

EDWARD J. BRANDT.
